UNITED STATES PATENT OFFICE.

GEORGE R. BROWNRIGG AND JACOB SUTZIN, OF MINNEAPOLIS, MINN.

LIGHTING DEVICE FOR FARE-BOXES.

SPECIFICATION forming part of Letters Patent No. 361,860, dated April 26, 1887.

Application filed November 12, 1886. Serial No. 218,688. (No model.)

To all whom it may concern:

Be it known that we, GEORGE R. BROWNRIGG and JACOB SUTZIN, citizens of the United States, residents of the city of Minneapolis, county of Hennepin, State of Minnesota, have invented a certain new and useful Improvement in Street-Car Fare-Boxes, of which the following is a specification.

Our invention relates to fare-boxes for street-cars and similar uses, and has for its object to thoroughly light up the interior of the fare-box from the same lamp which is used to light the body of the car.

In street-cars now in general use the three sides of the fare-box are made of glass, and a supplementary box is built adjacent to one of the glass sides of the fare-box proper, with a smoke-tube leading to the top of the car. On the bottom of this box, or a suitable shelf in the same, is placed a small lamp, which, through the glass partition between the lamp-box and the fare-box, throws an imperfect light into the fare-box. Another and larger lamp sits on a shelf near the top of the front end of the car and serves to light up the car.

The fare-box lamp is a constant source of annoyance. It is extremely uncertain. It burns irregularly. The glass soon becomes covered with smoke, and it greatly increases the risk of fire.

By our invention we dispense with the extra lamp altogether, saving the expense and avoiding the risk of fire, and obtain a much stronger and better light in the fare-box, where a good light is needed in order to enable the driver and passengers to see the fares.

Our invention consists of the device hereinafter described and claimed, reference being had to the accompanying drawings.

In the drawings, like letters referring to like parts throughout, Figures 1 and 2 are sectional elevations of the various forms of our invention as it appears in position for use.

A is the fare-box.

45 B is the car-lighting lamp resting on a shelf or bracket attached to the body of the car.

D is a bracket-arm supported in any suitable way on the side of the fare-box opposite to the lamp B.

50 C is a highly-polished reflector pivotally at-

tached to the arm D, so as to allow variation of its inclination to the vertical plane.

In Figs. 1 and 2 we show a light-conducting tube, E, extending from within the fare-box to above the lamp-shelf. This tube is highly polished on the inside, and is provided with one or more lenses for collecting and distributing the rays of light. These conducting-tubes will vary in length according to the position of the fare-box with reference to the lamp-shelf, the boxes in some cars being much lower than in others. The lenses will vary according to the necessities of the case.

K, Fig. 2, is concavo-convex, and in Fig. 1 we show a pair of lenses—a plano-convex at 65 the top and a double concave lens at the bottom of the tube.

The great object is to get a strong light on the fare-dumps in the fare-box. The lenses serve to distribute the light exactly where 70 needed. The reflector C has a concave highly-polished interior surface, and is formed as nearly as possible to the lines of exact mathematical curves.

In Figs. 1 and 2 the curve of the reflector 75 is an ellipse, and the lamp-flame is at one focus and the lens on top the conducting-tube is at the other; hence the rays from the lamp will be reflected on converging lines, meeting in the top lens. The rays pass from the top lenses 80 on convergent lines in Fig. 1, and in Fig. 2 the rays cross near the center of the tube, again diverging and filling the box. In Fig. 1, after crossing within the tube, the rays are further refracted by the lens H, and pass on divergent 85 lines into the fare-box. The focus of the rays from the lens G is below the center of the tube, a lens of greater or less convexity being used according to the length of the tube E.

M is a deflecting-mirror attached to the 90 lower end of the tube E, for catching and reflecting into the bottom of the box any scattered rays of light that otherwise would pass off to one side into the upper space of the box where not needed.

We have thoroughly tested our device and find that we can get a far better light where needed in the fare-box than by the extra side lamp now in general use.

We save the first cost of the extra lamp, the 100

cost of oil, breakage, and attendance, avoid smoke and risk of fire, and get a certain, reliable, and strong light.

We take from the car-lamp only such a part 5 of its rays as would be otherwise wasted.

Both forms shown in the drawings will work more or less perfectly and give a better light than the extra side lamp now in general use, and we desire protection, broadly, on all the 10 forms shown and their equivalents; but the form shown in Fig. 1 is our preferred construction, and this we desire to claim specifically.

What we claim, and desire to secure by Letters Patent of the United States, is as follows:

15 1. In street-cars, fare-box A, car-lamp B, conducting-tube E, provided with collecting and distributing lens at its top, as described,

and reflector C, arranged and supported with reference to lamp B, as described, and deflector M, attached to bottom of tube E, as described, 20 in combination, for the purpose set forth.

2. In street-cars, fare-box A, car-lamp B, conducting-tube E, lens G at the top of said tube, and lens H at the bottom of the same, reflector C, arranged and supported with reference to lamp B, as described, and deflector M, in combination, all substantially as described, for the purpose set forth. 25

GEORGE R. BROWNRIGG.
JACOB SUTZIN.
